UNITED STATES PATENT OFFICE.

OSCAR A. WIRKKALA, OF KENT, WASHINGTON.

BULL HOOK.

Application filed July 16, 1924. Serial No. 726,410.

To all whom it may concern:

Be it known that I, OSCAR A. WIRKKALA, a citizen of the United States, and a resident of Kent, in the county of King and 5 State of Washington, have invented a new and useful Bull Hook, of which the following is a specification.

My invention relates to improvements in bull hooks, more especially the kind used in 10 heavy logging, and one of the objects of my improvements is to provide a bull hook which is engageable and disengageable with the service cable without requiring more slack therein than is needed to relieve the 15 tension therefrom. Another object of my improvements is to provide a bull hook that is connected to the hauling cable and to the service cable without the usual eyes spliced in the ends of said cables. Another object 20 of my improvements is to provide a bull hook having swivel connections with both the hauling and service cables. Another object of my improvements is to provide a bull hook that makes a positive engagement with 25 the service cable. Another object of my improvements is to provide a positive hook having keeper mechanism disposed in a manner to protect it from injury during hook operations yet readily accessible for 30 operative changes. And a further object of my improvements is to provide a bull hook designed for casting in steel with a distribution 35 of the metal advantageous for strength and lightness, and smoothness of contour and compactness.

I attain these objects with the mechanism illustrated in the accompanying sheet of drawings in which Figure 1 is a top plan view of my hook, Fig. 2 is a front elevation, 40 Fig. 3 is a bottom plan view of Fig. 2 and Fig. 4 is a side elevation of Fig. 2.

Similar characters refer to similar parts throughout. Certain parts are broken away to show other parts hidden thereby.

More particularly: The main body of the hook is a hollow cylinder 5, the interior walls of which are shown at a^5 , having its upper end closed except for central hole 6 through which hauling cable 7 enters. On 50 the inner end of cable 7 is fixed knob 8, preferably, in a manner disclosed in my Patent Number 1,496,142, June 3, 1924. Hole 6 is smaller than chamber a^5 and knob 8 bears on the interior flange surrounding 55 said hole when cable 7 is under strain. The lower end of the hook body has two hori-

zontal jaws 9 and b^9 which unite at 10 in the rear of the hook body. Said jaws are spaced apart at a^9 wide enough to admit service cable 11 to a central position in 60 chamber a^5 , longitudinally. On the inner end of cable 11 is fixed cable knob 12 which, when said service cable is engaged by the hook, bears on top of jaws 9 and a^9 when 65 said cable is under operative strain. The front of hook body 5 is open at b^5 enough to permit knob 12 to enter chamber a^5 with its lower end in contact with the top surface of jaws 9, b^9 . In jaws 9 and b^9 are recesses 13 and a^{13} opposite each other. In these 70 recesses are housed keeper 14, dog 16 and spring 20. Recess a^{13} in jaw b^9 is only sufficient to house and provide a stop for the free end of keeper 14 when in operative position, while recess 13 has capacity to house 75 the pivoted end of keeper 14 and said dog and spring. Keeper 14 is pivoted by cap screw 15 in jaw 9 and can oscillate on its pivot from its full-line to its dotted-line position in Fig. 3. Dog 17 is pivoted by 80 cap screw 17 in jaw 9 and has bit 18 and tail 19, and can oscillate from its full-line to its dotted-line position in Fig. 3. When in its full-line position it is engaged with tooth a^{14} of keeper 14, and in its dotted-line 85 position it is disengaged from said keeper. Spring 20 reacts between jaw 9 and tail 19 of dog 16 to maintain bit 18 engaged with tooth a^{14} . Pressure from the finger of an operative on tail 19 will cause said dog to 90 pass to its dotted-line position out of engagement with keeper 14. Then if cable 11 is not under too great strain said cable and knob 12 can be removed from jaws 9, b^9 and thus disengaged from the hook. To 95 replace cable 11 in engagement with the hook, if keeper 14 is closed, pressure on tail 19, as described, will release said keeper and it can be swung on pivot 15 to its open position at 14' when said cable and knob can 100 be installed within the hook and with the closing of keeper 14 are positively engaged therewith.

The embedded disposition of the keeper mechanism is useful in practice as it prevents injury thereto as the hook is hauled with its cables along the ground, over logs and through brush. The hollow cylindrical form of the hook body allows an efficient distribution of the metal of the hook body 105 for strain-resisting purposes. The absence of obstructions on the upper surface of the 110

jaws allows the engagement and disengagement of the hook without slack in the cables. The freedom of both cable attachments to the hook to revolve provides a swiveling feature that is very useful and is obtained by simple means. In practice, operatives are well pleased with the design of this hook for it dispenses with the need of spliced eyes at the cable ends. These are always accompanied with protruding wire ends which cause injury to the hands of said operatives. Furthermore the extreme lightness of this design provides a sufficiently strong hook that is easily portable when used with cables one and one-half inches in diameter.

Having thus disclosed my invention, what I claim as new and desire to secure by Letters Patent is,—

1. In a logging hook in combination, a hollow hook body having means on its upper end for the attachment of a hauling cable thereto and having an opening through its front wall near its lower end for the passage of a service-cable knob therethrough, transverse jaws on the lower end of said hook body having a slot therebetween adapted to receive a service cable and having an upper surface adapted to seat said service-

cable knob, and a removable keeper disposed in recesses in said jaws and adapted to bar 30 said jaw slot in front of said service cable whereby said service cable is removably retained between said jaws with said service-cable knob on top thereof.

2. In a logging hook in combination, a 35 hollow hook body having a hole through its upper end, a hauling cable end inserted in said hole and protruding within said hollow body, a cable knob fixed to said hauling cable end within said hollow hook body 40 whereby said hauling cable is positively engaged with said hook body and free to revolve therein, two jaws on the lower end of said hook body spaced to receive a service cable therebetween and having an upper surface adapted to seat a cable knob, a service cable having a cable knob fixed on the end thereof between said jaws with said knob bearing on top thereof, and a keeper removably disposed as a bar across said jaws in 50 front of said service cable whereby said service cable is removably and positively engaged with said hook body and free to revolve therein.

OSCAR A. WIRKKALA.
